UNITED STATES PATENT OFFICE.

ADAM LANGE AND CARL LANGE, OF ST. LOUIS, MISSOURI.

IMPROVEMENT IN SHOW-CASES.

Specification forming part of Letters Patent No. **158,504**, dated January 5, 1875; application filed August 12, 1874.

To all whom it may concern:

Be it known that we, ADAM LANGE and CARL LANGE, both of St. Louis, county of St. Louis and State of Missouri, have invented an Improved Show-Case, of which the following is a specification:

This invention consists in the peculiar combination of show-cases, as will now be more fully described.

Of the drawing, Figure 1 is a perspective view of our show-case. Fig. 2 is a transverse sectional elevation at line *x x*.

A is the lower show-case; *B*, the top show-case. *C* is the frame-bottom. Surrounding the bottom *C* we secure the panel-bottom frame *c* for the front, *c*¹ *c*² for the sides, and *c*³ for the rear. Said frames *c* *c*¹ *c*² *c*³ have the groove feature for the securing of the glass panes. The united side frames are indicated by *d* *d*¹, and also are grooved for the reception of the glass.

As shown in the drawing, the show-case is illustrated so that its bottom case, *A*, at front, is partly rounded, while the top case, *B*, is square-shaped; hence the side frames *d* *d*¹ compose both shaped features, and answer for both sides of both cases. The glass panes *d*² *d*³ are correspondingly shaped, and, properly secured, complete the full sides for both cases.

D is the front glass pane. This is similarly shaped to the curve of the side frames *d* *d*¹,

and secured thereto, as well as to the center grooved panel-strip *E*, which unites said side frames. *e* *e*¹ are the remaining grooved panels that unite the side frames, and complete the top frame for case *B*. *e*² is the glass for front of the top case, and *e*³ glass to cover the top of top case. The open rear of the two cases *A* *B* we provide with hinged or sliding glass doors, *E*.

It is apparent that the articles, goods, and the like in the lower case, *A*, have the benefit of full display; likewise the goods and the like in the top case, *B*, and thus the display of contents in either of said cases is in no wise obstructed, and especially is there a greater and more adequate space for the display obtained.

Any number of glass shelves, *f*, can be provided.

What we claim is—

The bottom and top cases *A* *B*, having panels *E*, *c*, *c*¹, *c*², and *c*³, side panels *d* *d*¹, panes *d*² *d*³ *D* *e*² *e*³, and transparent doors *F*, forming the complete show-case, as herein shown and described.

In testimony of said invention we have hereunto set our hands.

ADAM LANGE.
CARL LANGE.
